UNITED STATES PATENT OFFICE.

CHARLES L. WOOD, OF WOBURN, MASSACHUSETTS.

TOY OR GAME.

1,115,642.

Specification of Letters Patent.

Patented Nov. 3, 1914.

Application filed March 18, 1914. Serial No. 825,684.

To all whom it may concern:

Be it known that I, CHARLES L. WOOD, a citizen of the United States, residing in Woburn, in the county of Middlesex and 5 State of Massachusetts, have invented an Improvement in Toys or Games, of which the following description, in connection with the accompanying drawings, is a specification, like characters on the drawings 10 representing like parts.

This invention relates to a game or toy apparatus having an inclined runway down which a marble, ball or other device travels into a receptacle at the lower end of the 15 runway.

The invention has for its object to provide a game or toy of the character described with an inclined runway having means intermediate its ends to cause a ball 20 or like device to jump into the air as it passes down the runway. It is preferred to make the runway of two members, which coöperate to form a continuous runway, and one of which is provided with a nose for 25 causing the ball or other device to jump into the air as it passes from one member to the other. Provision may and preferably will be made for enabling the ball or other device to be returned to the operator as will 30 be described. These and other features of this invention will be pointed out in the claims at the end of this specification.

Figure 1 is a plan, and Fig. 2, a side elevation of a game or toy apparatus embodying this invention. Figs. 3 and 4 are side elevations of the apparatus shown in Fig. 1, and illustrating the manner in which the ball or other device is returned to the operator.

40 In the present instance, I have shown one construction of apparatus embodying this invention, which consists essentially of two members *a*, *b*, pivoted to uprights *c*, *d*, erected upon a base *e*, said members being 45 provided in their upper surfaces with grooves or channels 10, 12, which coöperate to form a runway in which travels a device, herein shown as a ball or marble 13, but which may be any other device, such as 50 the well known roly-poly. The member *b* is provided at its lower end with a box or receptacle 14, preferably shaped like a triangle and having erected upon its bottom a plurality of pins 15 forming spaces for 55 the reception of the ball, said spaces being

numbered from 1 to 5 in the present instance. The box or receptacle 14 may and preferably will be provided with a pin or like device 16, which is located near the apex of the box and in line with the longitudinal center of groove 12, so as to be struck by the ball and thereby cause the latter to be deflected to one or the other side of the box, and thus render it uncertain in which space the ball will come to rest. 60

The grooves 10, 12 in the two members coöperate to form a runway, down which the ball 13 travels, and provision is made for causing the ball to jump into the air as it leaves one groove and to land in the 70 groove of the other member. To this end, the member *a* is provided at its lower end with an upwardly inclined portion or nose 20, which, in the normal or operative position of the apparatus shown in Fig. 2, projects above the upper end of the member *b* but in line therewith, so as to cause the ball to jump off from the nose 20 into the air and descend again into the groove of the member *b*. The nose 20 is preferably provided on 75 its under side with a slot 21 indicated by dotted lines, into which extends a tongue or projection 22 on the end of the member *b*. The nose 20 also serves to turn the member *b* on its pivot, so as to elevate the box 14 80 as represented in Fig. 3, in which position the ball 13 is caused to run back from the box, through the groove 12 and into the groove 10 in the nose 20, and when the ball is thus positioned, the operator turns the 85 member *a* on its pivot, so as to elevate the nose 20 and lower the starting end of the member *a* as represented in Fig. 4, and thereby cause the ball to be returned to the 90 operator. The downward movement of the starting end of the member *a* may be limited or arrested by a post 95 25 on the base *e*.

It will thus be seen, that the operator such as a child can start the ball or other device 13 at one end of the apparatus, and cause it to travel down the member *a* and jump over the nose 20 and into the groove of the member *b*, and then pass into the box or receptacle 14 and come to rest in a numbered space, and by turning the member *a* into the position shown in Fig. 3, and then into the position shown in Fig. 4, the ball is automatically returned from the box or receptacle 14 to the starting end of the mem- 100 105 110

ber *a*, ready to be again started on its way to the box or receptacle. The base *e* may be provided intermediate its ends with a cross bar 30, which may and preferably will be pivoted to the base, so that it can be turned crosswise thereof and afford a broad bearing for the apparatus when in use, or which can be turned under the base so as to extend in the direction of the length thereof for 10 shipping purposes.

I have herein shown one construction of apparatus embodying the invention, but it is not desired to limit the invention to the particular construction shown.

15 Claims—

1. In a game apparatus of the character described, in combination, grooved members coöperating to form an inclined runway, and independently pivoted, a box or receptacle coöperating with one of said members to receive a device from said member and provided with marked spaces for the reception of said device, and a nose on the normally lower end of the other or upper of 25 said members, for the purpose specified.
2. In a game apparatus of the character described, in combination, a pivoted upper runway member, a pivoted lower runway member, a receptacle attached to said lower 30 runway member, and means on the upper runway member coöperating with the lower

runway member to turn the latter on its pivot, substantially as described.

3. In a game apparatus of the character described, in combination, a pivoted upper 35 runway member, a pivoted lower runway member, and means on the upper runway member coöperating with the lower runway member to turn the latter on its pivot, for the purpose specified. 40

4. In a game apparatus of the character described, in combination, a pivoted upper runway member provided with an upwardly extended nose at its lower end, and a pivoted lower runway member with which said nose 45 coöperates, substantially as described.

5. In a game apparatus of the character described, in combination, an inclined upper runway member, an inclined lower runway member, and a nose on the lower end of the 50 upper runway member projecting above the upper end of the lower runway member and inclined upwardly above the upper surface of said lower runway member.

In testimony whereof, I have signed my 55 name to this specification in the presence of two subscribing witnesses.

CHARLES L. WOOD.
